APPARATUS FOR CONVERTING HEAT AND
PRESSURE ENERGIES INTO MECHANICAL
ENERGY

Edward T. Turner, Dayton, Ohio

Application January 27, 1938, Serial No. 187,252

6 Claims.

(Cl. 60—63)

This invention relates to an apparatus for converting heat and pressure energies into mechanical energy.

One object of the invention is to provide a simple and efficient apparatus for converting the heat and pressure energies of a highly heated liquid into mechanical energy.

A further object of the invention is to provide an apparatus for utilizing products of combustion, taken either directly from the furnace or from the flues of a boiler, to impart a high temperature and high pressure to a liquid and then converting the heat and pressure energies of said liquid into mechanical energy.

A further object of the invention is to provide a simple efficient apparatus for producing power in which more heat may be extracted from the products of combustion than is possible with the usual boiler plant.

A further object of the invention is to provide an apparatus for utilizing flue gases from a boiler to heat water to a temperature and pressure in excess of the temperature and pressure of the water in said boiler and then converting the heat and pressure energies of the water so heated into mechanical energy.

A further object of the invention is to provide an improved power cycle in which a liquid is heated under pressure to its temperature of vaporization, then converted into mechanical energy at a lower pressure and then restored to its initial temperature and pressure.

Other objects of the invention may appear as the apparatus is described in detail.

In the accompanying drawings Fig. 1 is a diagrammatic view, partly in section, of an apparatus embodying my invention; Fig. 2 is a similar view of a portion of a modified form of the apparatus; Fig. 3 is an elevation, partly in section, of a form of the apparatus which embodies a two stage power apparatus; Fig. 4 is a longitudinal section of a portion of the conduit connecting the two units of the power apparatus; and Fig. 5 is a transverse section taken on the line 5—5 of Fig. 4.

In Fig. 1 I have shown, for the purpose of illustration, an apparatus which utilizes the flue gases from a boiler, which would otherwise be discharged to waste. These flue gases are passed in counterflow heat exchange relation to a supply of water, the arrangement being such that the water may be heated to a temperature and a pressure substantially in excess of the temperature and pressure of the water in the boiler. This highly heated water at high pressure is passed through an expansion nozzle which serves

to reduce the pressure on the water so as to cause a portion of the water to be converted into steam and expanded to impart velocity energy to the mixture of steam and water which is discharged from the nozzle. The mixture so discharged from the nozzle is then utilized to operate a power element.

In the particular arrangement shown in the drawings the water in the boiler 1 is heated by a furnace 2 in the usual manner to generate steam at a predetermined temperature and pressure, this steam being delivered to a steam chest 3 from which it may be taken through a conduit 4 to operate a power element or to perform other useful work. The flue gases, or products of combustion, are delivered from the boiler through a discharge passageway 5 to a heat exchanger which is preferably of the counterflow type and is here shown as comprising an elongate casing 10 or shell 6 connected at one end with the passageway 5 and having at its other end an outlet 7 through which the gases may be discharged to the stack or other suitable point of discharge, the casing thus constituting a conduit for the flue gases. Arranged within the conduit 6 is a water conduit 8 having at one end thereof an inlet pipe 9 which projects beyond that end of the conduit 6 opposite the inlet passageway 5 to provide means for connecting the water conduit with a suitable source of water supply, not here shown. The other end of the water conduit 8, that is the end adjacent the inlet for flue gases, is connected with a conduit 10 which leads to a casing 11 in which is mounted a power element, such as a Pelton wheel 12. The conduit 10 includes an expansion nozzle 13 which discharges directly into the casing 11. Preferably a flow equalizer 14 is connected with the conduit 10 adjacent the discharge end of the water conduit 8 of the heat exchanger, to provide a substantially uniform flow of water through the conduit 10 and nozzle 13. The water conduit 8 may be connected with the conduit 10 at any suitable point but if connected with that conduit between the flow equalizer 14 and the nozzle 13 water entering the flow equalizer more rapidly than it is discharged through the nozzle to the power element will have a tendency to compress the steam in the equalizer which will tend to increase the pressure above the pressure of vaporization for the temperature carried. I therefore prefer to connect the conduit 8 with the steam space in the equalizer drum and to provide the conduit within the equalizer with a spray head 14a so that the water will be discharged into the steam in the

form of a spray, which will serve to condense the steam in the steam space as its pressure rises. In this manner the incoming water will maintain substantially a constant pressure and temperature within the equalizer irrespective of variations in the level of the water therein. The flow equalizer 14 may conveniently be provided with a vent or air relief valve 15 to enable any air which enters the equalizer to be withdrawn and thus permit the temperature of vaporization of the water to be reached without wasteful pumping energy. 10

The flue gases are discharged from the boiler to the heat exchanger at a temperature in excess of the temperature of the water within the boiler and the arrangement of the two conduits of the heat exchanger is such that the water during its travel through the heat exchanger will be heated to a temperature and pressure substantially greater than the temperature and pressure of the water in the boiler. As this water at high temperature and high pressure passes through the expansion nozzle 13 the pressure on the water is reduced and a portion of the water is converted, or flashed, into steam, which is expanded in the nozzle and mixed with the water therein to convert heat and pressure energies into velocity energy, and this velocity energy is imparted to the mixture of the water and steam which is discharged from the nozzle, the effluent mixture acting directly upon the power element to actuate the latter.

It is preferable that means be provided for controlling the amount of water delivered to the expansion nozzle, and thus governing both the volume and velocity of the effluent mixture. However, the controlling means should be of a character that will not cause or permit of the vaporization of any part of the water before the latter enters the nozzle. Such a controlling means may conveniently comprise a valve member 16, of the needle type, arranged to cooperate with the restricted portion of the passageway through the nozzle. As there shown, the nozzle has at its inlet end a chamber 17 with which the conduit 10 is connected. The valve is mounted for movement in line with the nozzle passageway, preferably by a screw threaded connection between the same and the end wall of the chamber 17. The adjustment of the valve will vary the capacity of the inlet to the nozzle and thus control the delivery of water thereto but the chamber 17 and conduit 10 will at all times be full of water under pressure and this head of water will prevent the vaporization of any part of the water before it enters the nozzle.

After the mixture of steam and water has acted on the power element it may be disposed of in any suitable manner. It is preferable, however, that this fluid should be returned to the heat exchanger or other source of heat, in the interest of economical operation. The steam may be condensed and the condensed steam and the water, or either of them, may be returned to the heat exchanger and again utilized. The apparatus shown in Fig. 1 is adapted to condense the steam and again utilize both the condensed steam and the water and is of such a character that the water will be separated from the steam within the casing 11 and withdrawn from the lower portion of the casing, as by means of a pump 18 which delivers the same to a tank or other receptacle 19. The steam is withdrawn from the casing 11 through an outlet conduit 20, preferably connected with the upper portion of

the casing, and is delivered to a condenser 21. The condensate is withdrawn from the condenser, as by means of a pump 22, and is also delivered to the receptacle 19. The liquid in the receptacle 19, including both the withdrawn water and the condensate, are then delivered by means of a pump 23 and a conduit 24 to the heat exchanger, the conduit 24 being here shown as connected with the supply pipe 9 leading to the water conduit of the heat exchanger. In this manner a complete cycle of operations is provided and the same water may be used over and over again with the addition of only so much new water as is necessary to supply losses. By delivering the water and condensate to an open tank before returning the same to the heater any air contained therein is removed, and the rate of return to the heat exchanger may be modified to correspond to the water requirements at the power element. 15
20
25

The water usually contains some solids and to prevent these solids from accumulating in an objectionable quantity it is desirable to discharge a portion of the water to waste during each cycle of operation. For this purpose the conduit leading from the pump 18 to the tank 19 may be provided with a restricted outlet, 19a, in the nature of a blowdown. 30

The method has been described in connection with an apparatus designed to use flue gases from a boiler plant in the heat exchanger, but this is not necessary to the operation of the method and it will be obvious that the heat exchanger may take the products of combustion directly from a furnace, or other place of fuel consumption, without otherwise affecting the method and apparatus. When the heat exchanger takes the products of combustion directly from the burning fuel it will ordinarily be used as a substitute for a steam boiler and steam power generating equipment rather than as a supplement for the same. Such a high pressure high temperature plant may be constructed at a much lower cost than steam plants of much lower pressures and temperatures, and high temperatures and pressures are of course conducive to high efficiencies. The space occupied by such a plant would be small compared to the space occupied by steam plants and it is possible to provide the same of such compact construction as to adapt it for use on locomotives. The design of the countercurrent heat exchanger is such that its efficiency may substantially exceed the efficiency of steam boilers and its efficiency may be as high as that of a steam boiler and an economizer combined, although the cost of a heat exchanger would be far less than that of a steam boiler without the economizer. Consequently the substitution of a high pressure high temperature apparatus embodying my invention would greatly reduce the fuel consumption with a corresponding saving in the cost of operation. It is recognized that for a given pressure the proposed cycle efficiency is not as high as the steam cycle. However, the highly efficient heat exchanger, with the high pressures and high temperatures that may be used with the apparatus, plus the high efficiency of the Pelton type of wheel, as compared to steam turbines, result in a much higher overall efficiency than can be attained in the lower pressure steam plants. 75
Further, the supply of water at high temperatures and high pressure may be taken from a suitable source of supply without the use of a heat exchanger. For example, many boilers are provided with a device, commonly known as a continuous blowdown, for removing sediment or

solids from the boiler, and when such a continuous blowdown is used, as shown at 25 in Fig. 2, a continuous stream of water at high temperature and high pressure is discharged from the boiler and by connecting this continuous blowdown with the expansion nozzle 13a, as by a conduit 10a, the water thus discharged may be passed through the expansion nozzle 13a and sufficient velocity energy will be developed to enable the effluent mixture to operate a power element having a substantial power capacity. The power element is here shown as a Pelton wheel 12a mounted in a casing 11a into which a nozzle 13a discharges. In this apparatus, as well as in the apparatus of Fig. 1, the pressure of the fluid in the expansion nozzle will be reduced below atmospheric pressure. The steam is separated from the water in the casing 11a and discharged to a condenser 21a from which it is withdrawn by a pump 22a and the discharge side of this pump may, if desired, be connected directly with the boiler, or with a feed water line leading to the boiler, so that the condensate will be again heated and utilized. The water may be withdrawn from the casing 11a by a pump 18a but inasmuch as this water will contain solids which it is not desirable to return to the boiler the water, or at least a portion thereof, will usually be discharged to waste. In an installation of this character it is desirable to carry a high vacuum in the condenser. If, for example, a vacuum of twenty-eight inches is carried in the condenser the down-blow water which goes to waste will have a temperature of approximately 100° and therefore very little heat will be left in the waste water, and the heat which ordinarily goes to waste in such water is effectively utilized.

In some installations the efficiency of the apparatus may, if desired, be further increased by utilizing a two stage power unit, preferably the Pelton type. For this purpose two power elements are used and the mixture of steam and water, after acting on the first power element, is caused to act on the second power element by passing the same through a second expansion nozzle in which another portion of the water is converted into steam and expanded, along with the steam previously generated, to impart additional velocity energy to the mixture of steam and water which is discharged to the second power element. The mixture of steam and water may, if desired, be taken from the casing of the first power element without separating the same and delivered to the second nozzle in its mixed condition, but I prefer to separate the steam and water and then deliver the same to the second nozzle in the manner shown in Fig. 3. As there shown, the first power element is shown as a Pelton wheel 26 mounted in the casing 27 to which the mixture of steam and water is delivered through an expansion nozzle 28. The water is withdrawn from the lower portion of the casing through a conduit 29 and the steam is withdrawn from the upper portion of the casing through a conduit 30, all substantially as shown in Fig. 1. The second power element 31 is shown as a Pelton wheel similar to the Pelton wheel 26 but provided with blades, or pockets, of a capacity greater than the capacity of the blades of the Pelton wheel 26. The Pelton wheel 31 is mounted in the casing 32 with which communicates an expansion nozzle 33. This nozzle is provided at its inlet end with a chamber 34 with which the steam conduit 30 is connected, the

steam preferably entering the chamber at right angles to the passageway through the nozzle. The water conduit 29 is connected with the chamber 21 in line with the passageway through the nozzle and as the water is discharged into the chamber 34 it will be mixed with the steam from the conduit 30 and when this mixture is passed through the nozzle 33 an additional portion of the water will be converted into steam. This steam, together with the steam from the conduit 30, will expand in the nozzle to convert heat and pressure energies into velocity energy and thus impart to the effluent mixture an increased velocity energy. In order that there may be an intimate mixture of steam and water in the chamber 34 I have provided means for discharging the water into that chamber with a whirling motion, this being accomplished in the present instance by inserting in the conduit 20, adjacent to the chamber 34, a plate 35 which is partially spiral in form. As shown this plate is secured at its lateral edges to the walls of the conduit and is twisted through approximately one-fourth of a rotation about a longitudinal axis so that the transverse edge of the plate at its discharge end will extend at approximately right angles to the transverse edge of the plate at its intake end.

The steam and water may be withdrawn from the second casing 32 and disposed of in any suitable manner but, as here shown, the casing has a water outlet 37 at its lower end and a steam outlet 38 in the upper portion thereof, whereby the steam and water are separated and separately withdrawn so that the steam may be condensed and the condensate and water returned to the source of heat in the same manner as shown in Fig. 1.

While I have shown and described certain forms of my apparatus for performing the same I wish it to be understood that I do not desire to be limited to the details thereof as various modifications may occur to a person skilled in the art.

Having now fully described my invention what I claim as new and desire to secure by Letters Patent is:

1. In an apparatus of the character described, a conduit, means for connecting said conduit with a source of supply of products of combustion, a second conduit arranged in counterflow heat exchange relation to the first mentioned conduit, means for connecting the inlet end of said second conduit with a source of supply of water, a flow equalizer connected with the discharge end of said second conduit, a casing, a conduit leading from said flow equalizer to said casing and including an expansion nozzle to convert a portion of the water into steam and expand said steam to impart velocity energy to the mixture of water and steam, and a power element arranged in said casing to be actuated by said mixture of water and steam.

2. In an apparatus of the character described, a conduit, means for connecting said conduit with a source of supply of products of combustion, a second conduit arranged in counterflow heat exchange relation to the first mentioned conduit, means for connecting said second conduit at one end with a source of supply of water, a flow equalizer having a steam chamber in the upper portion thereof, means for spraying water from said second conduit into said steam chamber, a casing, means for connecting said flow equalizer with said casing and including an ex-

pansion nozzle to convert a portion of the water into steam and expand said steam to impart velocity energy to the mixture of water and steam, and a power element arranged in said casing to be actuated by said mixture of steam and water.

3. In combination with a source of supply of water at high temperature and high pressure, a casing, a conduit leading from said source of supply to said casing and having at its discharge end an expansion nozzle to convert a portion of said water into steam and expand said steam to impart velocity energy to the mixture of steam and water, a power element arranged in said casing to be actuated by said mixture of water and steam, a second casing, means for delivering water and steam from the first mentioned casing to said second casing, said means including an expansion nozzle to convert an additional portion of said water into steam and expand said steam and the steam from the first mentioned casing to impart additional velocity energy to the mixture of steam and water which is discharged from said second casing, and a power element arranged in said second casing to be actuated by the last mentioned mixture of water and steam.

4. In combination with a source of supply of water at high temperature and high pressure, a casing, a conduit leading from said source of supply to said casing and having at its discharge end an expansion nozzle to convert a portion of said water into steam and expand said steam to impart velocity energy to the mixture of steam and water, a power element arranged in said casing to be actuated by said mixture of water and steam, a second casing, means for separately withdrawing water and steam from the first mentioned casing and mixing said steam with said water, an expansion nozzle arranged to receive said mixture of water and steam, convert another portion of said water into steam and expand all of said steam to impart velocity energy to said mixture and deliver the same to said second casing, and a power element arranged in said second casing to be actuated by the last mentioned mixture of water and steam.

5. In combination with a source of supply of water at high temperature and high pressure, a casing, a conduit leading from said source of supply to said casing, and having at its discharge end an expansion nozzle to convert a portion of said water into steam and expand said steam to impart velocity energy to the mixture of steam and water, a power element arranged in said casing to be actuated by said mixture of water and steam, a second casing, an expansion nozzle communicating with said second casing and having a chamber at its inlet end, a conduit to deliver steam from the first mentioned casing to said chamber, a second conduit to deliver water from the first mentioned casing to said chamber and having means for discharging said water into said chamber with a whirling motion, whereby the steam and water in said chamber will be intimately mixed and delivered to the last mentioned nozzle, said last mentioned nozzle being shaped to convert another portion of said water into steam and to expand all the steam therein to impart velocity energy to the mixture of steam and water, and a power element arranged in said second casing to be actuated by the mixture of steam and water which is discharged from said last mentioned nozzle.

6. In combination with a source of supply of water at high temperature and high pressure, a casing, a conduit leading from said source of supply to said casing and having at its discharge end an expansion nozzle to convert a portion of said water into steam and expand said steam to impart velocity energy to the mixture of steam and water, an equalizer interposed between said source of water supply and said expansion nozzle and arranged at a substantially higher level than said nozzle, the arrangement of said parts being such as to maintain a head of water under substantially constant pressure in said conduit in advance of said nozzle, and a power element arranged in said casing to be actuated by the mixture of steam and water discharged from said nozzle.

EDWARD T. TURNER.
